UNITED STATES PATENT OFFICE.

WILLIAM EDWARD GREGORY, OF ASTORIA, OREGON.

DESIGN FOR A SHOE-HORN CLAMP.

SPECIFICATION forming part of Design No. 28,468, dated April 12, 1898.

Application filed July 10, 1897. Serial No. 644,150. Term of patent 14 years.

To all whom it may concern:

Be it known that I, WILLIAM EDWARD GREGORY, a citizen of the United States, residing at Astoria, in the county of Clatsop and state of Oregon, have invented and produced a new and original Design for a Shoe-Horn Clamp, of which the following is a specification.

Reference is to be had to the accompanying drawings, forming a part of this specification, in which—

Figure 1 is a side elevation of a shoe-horn clamp embodying the features of my design. Fig. 2 is a longitudinal section on the line 2, Fig. 3. Fig. 3 is a bottom plan view; and Fig. 4 is a section taken on the line 44, Fig. 3.

The design consists principally in the configuration of the shoe-horn clamp A, the forward portion *a* of which is concaved on one

side and convexed on the opposite side and is 20 merged into a handle portion B, the said handle portion being at an angle to the first-named portion *a* and concaved and convexed oppositely thereto, these two oppositely-disposed concavities at their adjacent ends being joined by the opening O.

A minor feature of the design consists in the projection C, rising from the concaved surface of the portion *a*, near the forward edge thereof. 30

I claim—

The design for a shoe-horn clamp herein shown and described.

WILLIAM EDWARD GREGORY.
